BRACELET END ATTACHMENT

Emil Rodriguez, New York, N. Y., assignor to Jacoby-Bender, Inc., New York, N. Y., a corporation of New York

Application June 16, 1954, Serial No. 437,065

18 Claims. (Cl. 24—265)

The present invention relates to a bracelet end attachment adapted to be inserted between spaced watch lugs and, within limits, to automatically adapt itself to variations in that space.

Many watches, and particularly men's watches, are provided with pairs of spaced lugs on each end, between which lugs the ends of a watch strap or bracelet are secured, usually by means of a spring pin passing through a hollow tubular part in the bracelet end and having tips adapted to be received in apertures formed in the watch lugs. There are a multitude of sizes and styles of watches, and a corresponding variation from watch to watch in the distance between the watch lugs. It is obviously impractical for a manufacturer or retailer of watch bracelets to make or stock bracelets in every style and in every possible width. It is not even feasible to make bracelets in a limited number of widths, as is done, and provide end attachments for the bracelets which are of exactly the right sizes to correspond to all of the various spacings between the watch lugs. These end attachments are usually an integral part of the bracelet, built thereinto by the manufacturer, and any such approach would require each retailer to maintain a tremendous inventory on the chance that a would-be purchaser might have a watch the lugs of which are spaced from one another by an unconventional distance.

On the other hand, it is most undesirable appearance-wise and functionally that when the bracelet is attached to the watch its ends should slide back and forth between the watch lugs, as would occur if the end attachment were narrower than the space between those lugs. Any gap between the bracelet end and the watch lugs is unsightly, and the relative sliding of the watch and bracelet end gives rise to a "sloppy" feeling, and has a tendency to pinch the skin of the wearer.

In the past this problem usually has been met by providing bracelets with end attachments in a limited number of standard widths, and by requiring the retail jeweler, when the bracelet is sold, to fit that bracelet to the customer's watch and to cut or file down the end attachments so as to give it a width corresponding accurately to the space between the lugs on the watch of that particular customer. This is a troublesome task, particularly in view of the fairly low profit made by the retailer on an individual sale. Furthermore, this expedient has not entirely solved the inventory problem of the retailer, since he still must stock bracelets of a given style having a plurality of different width end attachments.

It therefore is not surprising that it has been proposed in the past that self-sizing end attachments be provided. These have usually taken the form of a fixed end attachment having a minimal width, with members resiliently projected out from each end thereof so as to bridge the gap between the fixed portion of the end attachment and the lugs of the particular watch to which the bracelet is adapted to be secured. Numerous such constructions have been devised, but none of them have met with any real measure of public acceptance or permanency, primarily

2

because they are extremely unreliable. The tendency of the bracelet to move toward one lug or the other was resisted only by the necessarily weak spring acting between the movable members on the end attachment. The member pointing in the direction in which the bracelet moved would slide inwardly upon the exertion thereon even of minimal forces, the member on the other side of the end attachment was carried along, and consequently one of the main drawbacks to the use of fixed end attachments narrower than the space between the watch lugs, to wit, the relative sliding of bracelet and watch, while somewhat minimized, was not avoided by such structures. In addition, when the members resiliently urged outwardly from the fixed portion of the end attachment were themselves employed to engage with the watch lugs, dispensing with the use of a conventional spring pin, the above described action of the prior art self-sizing devices often resulted in separation of the bracelet from the watch, obviously an inadmissible situation.

20 A further drawback to the use of self-sizing end attachments of the prior art was that they were fairly difficult to manipulate, and thus made it difficult if not impossible for the average person to remove or attach a bracelet himself. This, of course, placed a burden on the retailer which, while perhaps not as onerous as the previous necessity for cutting or filing the end attachments to the proper width, was nevertheless undesirable. It must be realized that, under these circumstances, and apart from the time actually involved in attaching the bracelet to the watch, a potential sale would be lost if the would-be customer did not happen to have with him the watch with which the bracelet was to be used.

25 A further disadvantage characteristic of the prior art structures, important primarily from an appearance point of view, was that the bracelet would not always be centered between the watch lugs, but might assume a position closer to one lug than to the other.

30 The structure of the present invention avoids all of the above disadvantages, and involves a mechanism which, 40 while necessarily somewhat more complex than those suggested in the prior art, nevertheless is eminently capable of manufacture and assembly at such an extremely low cost as to be commercially practical. To this end the two members resiliently urged outwardly from opposite 45 ends of the fixed portion of the bracelet end attachment are connected to a movement-equalizing linkage, by means of which the positioning of one member relative to the fixed portion of the end attachment will necessarily cause a corresponding positioning of the other member. As 50 a result, the bracelet end attachment will always be centered between the watch lugs. This movement-equalizing linkage, when properly designed, can also serve two other extremely important functions. First, the linkage is so 55 designed as to resist and effectively prevent inward movement of the members when all but the strongest inward pressure is applied only to one of those members. Consequently any tendency of the bracelet to slide from side to side relative to the watch is practically eliminated. Second, the same linkage will also function, when the 60 resilient means serving to urge the members outwardly is active on those members through the intermediation of the linkage, to apply to the resilient means only a portion of any inward force which may be exerted on the members. Consequently a somewhat weaker spring may be 65 employed than has previously been the case without any sacrifice in operating characteristics or, conversely, the use of a spring of conventional strength will result in improved operation and reliability of the device.

70 In addition, it has been found quite feasible to incorporate into the end attachment a manually actuatable securing element which, when moved to operative position, will act to retain the members in contracted posi-

tion, preferably housed substantially completely within the fixed portion of the attachment. When the securing element is thus engaged with the movable members, the attachment may readily be inserted between the watch lugs, and when the attachment is properly positioned and the securing element is moved to inoperative position the members are released and are urged outwardly by the resilient means into engagement with the watch lugs, thus performing their self-sizing and centering function. Hence it is a simple matter, well within the capabilities even of the mechanically unskilled, to secure to a watch bracelet fitted with the end attachment of the present invention.

To the accomplishment of the above, and to such other objects as may hereinafter appear, the present invention relates to the structure of a bracelet end attachment as defined in the appended claims, and as described in this specification, taken together with the accompanying drawings, in which:

Fig. 1 is a three-quarter perspective view of a bracelet fitted with the end attachment of the present invention and showing the manner in which it is adapted to be secured to a watch;

Fig. 2 is a top plan view, partially broken away, of the end attachment with the ornamental top shell removed;

Fig. 3 is a bottom plan view thereof, with the linkage housing cross sectioned;

Fig. 4 is a cross sectional view taken along the line 4—4 of Fig. 2;

Fig. 5 is a view similar to Fig. 2 but showing the movable members in fully telescoped condition and with the securing element in operative position;

Fig. 6 is a fragmentary exploded view, partially in cross section, showing the linkage and resilient means of the embodiment of Figs. 1-5;

Fig. 7 is a view similar to Fig. 3 but showing another embodiment of the present invention;

Fig. 8 is a cross sectional view taken along the line 8—8 of Fig. 7; and

Figs. 9, 10, 11 and 12 are views similar to Fig. 2 but showing four other embodiments of the present invention.

Referring first to the embodiments of Figs. 1-6, the end attachment comprises a base plate 2 one end 4 of which is in hollow tubular form, the other end having a rear protrusion 6 provided with an elongated slot 8, another slot 10 being formed in the other side of the rear portion of the base plate 2, these slots being provided so that an X-type resiliently expandable bracelet generally designated 12 may be secured thereto in conventional manner. An ornamental shell 14 is adapted to cover the plate 2 and the mechanism thereon, the ornamentation on the shell 14 preferably corresponding to the ornamentation of the top shells 14a on the bracelet 12. It will be understood, of course, that any other type of bracelet or strap could be employed in place of the specific bracelet 12 illustrated, the base plate 2 being modified in conventional manner so as to be attached thereto.

The tubular part 4 of the base plate 2 is of predetermined minimal width such as to fit between lugs 16 on a watch case 18 when those lugs 16 are comparatively closely spaced. A pair of members 20 and 22 are provided telescopic within the hollow tubular portion 4 (see Fig. 5) and movable outwardly beyond the sides 24 and 26 thereof. In the form shown in Figs. 1-5, each of these members is formed from a single sheet of metal or the like rolled or bent to define a hollow tube, a conventional spring securing pin 28 (see Fig. 1) being adapted to be passed therethrough and through the hollow tubular part 4 of the base plate 2 so that the tips 30 of the spring pin 28 may be received within apertures 32 in the watch lugs 16. In order to provide access to the spring pin when the bracelet is to be removed, the outer end of one of the members, here shown as the member

22, is provided with a slot 34. In addition, the inner ends of each of the members 20 and 22 are provided with slots 36 and 38 respectively. Each of the members 20 and 22 is provided with rearwardly extending plates 40 and 42 respectively which are slideable along passages 44 (see Fig. 4) defined between the base plate 2 and the overhanging end of the tubular part 4. Extending downwardly from the central portion of the lower side of the base plate 2 is a housing generally designated 46 the upper portion of which may be open, as shown in Figs. 2 and 4. The bottom wall 48 of the housing 46 is provided with a slot 50 along which pin 52 slides, the slot 50 being oriented substantially at right angles to the length of the tubular part 4, that is to say, perpendicular to the width of the end attachment. A pair of arms 54 and 56 are provided respectively with hubs 58 and 60 freely rotatably fitted on the pin 52, and a helical spring 62 is wound about the pin 52 inside the hubs 58 and 60, the ends 96 and 100 of that spring 62, after 10 the spring has been stressed, being received within notches 64 and 66 formed respectively in the upper and lower surfaces of the hubs 58 and 60, the spring 62 being active to urge the arms 54 and 56 to rotate away from one another. The pin 52 may be provided with a head 68 in order to retain the hubs 58 and 60 on the pin 52 and the spring ends in their respective notches 64 and 66. As may best be seen from Figs. 4 and 6, the arms 54 and 56 are adapted to ride along the bottom wall 48 of the housing portion 46 and extend into the hollow tubular portion 4. The arms, at their ends, are provided respectively with trunnions 70 and 72 adapted to be received respectively in the slots 36 and 38 at the inner ends of the movable members 20 and 22, thus defining a 15 pivotal operative connection between each of the members 20, 22 and a corresponding arm 54, 56. The tendency of the spring 62 to separate the arms 54 and 56 will therefore cause the members 20 and 22 to slide outwardly beyond the sides 24 and 26 respectively of the tubular part 4, thus in effect extending the width of the end attachment so as to correspond to the spacing between the particular watch lugs 16 involved. When this occurs, the pin 52 will slide along the slot 50 in the direction of the tubular member 4.

If pressure is exerted on the members 20 and 22 so as to tend to move them into the tubular part 4, thus contracting the effective width of the attachment, this pressure will cause the arms 54 and 56 to swing toward one another against the action of the spring 62, the pin 52 sliding along the slot 50 in a direction away from the tubular part 4, and when pressure is released from the members 20 and 22 they will once again, under the influence of the spring 62, resiliently telescope outwardly to an extent limited only by the length of the slot 50, which restricts the degree to which the pin 52 can slide 20 toward the tubular part 4.

Because of the orientation of the slot 50, the pin 52 is restricted from movement in a direction widthwise of the attachment. Hence the members 20 and 22, when operatively connected to the arms 56 and 54 respectively, 25 must be correspondingly positioned relative to the tubular portion 4. As a result, the part of the attachment secured to the bracelet 12 will always be centered between the watch lugs 16 when the outer ends of the members 20 and 22 are in engagement with those lugs.

It will be noted that the arms 54 and 56 extend at an angle to the direction of movement of the members 20 and 22. As a result, when a given force is exerted upon the members 20 and 22 tending to cause them to telescope inwardly with respect to the tubular part 4, only a component of that force will be exerted on the arms 54 and 56 as a moment tending to cause them to pivot toward one another. It is only this moment which is active on the spring 62 to cause the latter to wind up. That component of the force exerted on the member 20 which is not applied to the spring 62 is partially opposed by an 30

opposite and substantially equal component of the force exerted on the member 22, the remainder of those components acting aidingly to slide the pin 52 along the slot 50. Consequently, for a given resistance to movement of the members 20 and 22, a weaker spring 62 may be employed than would be the case if the spring were directly active on the members 20 and 22 in the manner suggested by the prior art. Conversely, employment of a spring 62 of conventional strength will result in increased resistance of the members 20 and 22 to inward movement when compared to the structures of the prior art. The magnitude of the components of the forces exerted on the members 20 and 22 which will be applied to the spring 62 will increase as the arms 54 and 56 approach one another. At the same time the spring 62, being more and more wound up, will resist those forces to an increased degree. These effects at least to some extent compensate for one another, so that the resistance to inward movement of the members 20 and 22 is much more independent of their position relative to the tubular part 4 than would otherwise be the case.

That component of the inward force exerted on the members 20 and 22 which does not act on the spring 62 plays a further extremely important role. Let us assume that inward force is exerted only on the member 20, as would be the case if the bracelet, after being attached to the watch 18, tended to slide toward the watch lug 16 with which the member 20 was in engagement. One component of this force would tend to cause the arm 54 to pivot toward the arm 56. Another component thereof, however, would be exerted on the pin 52 in the direction in which the arm 54 extends. Part of this latter force component would tend to cause the pin 52 to slide along the slot 50 away from the tubular part 4, but another part thereof would tend to force the pin 52 against the side of the slot 50. This last component would be appreciable, its precise magnitude depending on the angularity of the arm 54 relative to the slot 50, the pin 52 will resist sliding, and consequently the arm 54 will not pivot. Hence the member 20 will strongly resist inward telescoping movement. It is only when inward pressure is exerted simultaneously on the members 20 and 22 that the pin 52 will freely slide along the slot 50, the force components tending to urge the pin 52 against the sides of the slot 50 cancelling one another out in that latter situation. Hence the linkage here disclosed has the additional extremely important effect of strongly resisting inward force exerted on only one of the members 20 and 22. Therefore the end attachment of the present invention will not only initially center itself between the watch lugs 16, but will reliably remain thus centered even when extremely appreciable forces are exerted thereon tending to move it toward one watch lug 16 or the other.

A securing element in the form of an arm 74 is pivotally mounted on the base plate 2 at 76 and is adapted to overlie the head 68 of the pin 52, thus serving to retain the pin 52 in position. The arm 74 is provided with a tab 78 extending downwardly through an arcuate slot 80 in the base plate 2, manual manipulation of the tab 78 causing the arm 74 to be moved between its inoperative position shown in Fig. 2 and its operative position shown in Fig. 5. The arm is provided with teeth 82 and 84 engageable with corresponding teeth 86 and 88 on the plates 40 and 42 respectively when the members 20 and 22 are substantially fully telescoped within the tubular part 5, the arm 74 thus retaining the members 20 and 22 in their retracted position, the effective width of the attachment thus being maintained at its minimal value. This facilitates insertion of the attachment between the watch lugs 16 and the securing of the spring pin 28 to those lugs 16. After this has been accomplished, the tab 78, accessible from beneath the attachment, is moved along the slot 80 so that the arm 74 is pivoted to its inoperative position releasing the teeth 86 and 88 on the plates 40 and 42 respectively, the spring 62 then being permitted to unwind

so as to cause the members 20 and 22 to telescope outwardly until they engage the watch lugs 16, the attachment thus spacing itself between the particular watch lugs 16 involved.

It will be appreciated that, because of the slot-trunnion operative connection between the members 20, 22 and the arms 54, 56, the members 20, 22 may be assembled merely by sliding them into the opposite ends of the tubular portion 4 until that operative engagement is effectuated. Thereafter tabs or other protrusions 90 may be struck up from the base plate 2 into the path of movement of the plates 40 and 42 so as to prevent the members 20 and 22 from sliding completely out of the tubular part 4.

The embodiment of Figs. 7 and 8 illustrates an attachment employing movable members 20' and 22' of a specifically different type from those employed in the embodiment of Figs. 1-6. In Figs. 7 and 8 those members are solid bars telescopic with respect to the fixed tubular portion 4 and carrying tips 30' at their ends, those tips 30' being adapted for direct engagement with the apertures 32 in the watch lugs 16, thus dispensing with the necessity for the employment of a separate spring pin 28. It will be understood that the tipped members 20' and 22' could be substituted for the tubular members 20, 22 in all of the other illustrated embodiments.

The embodiment of Figs. 7 and 8 also discloses a specifically different linkage between the members 20' and 22'. The base plate 2 is provided with the elongated slot 50 oriented substantially perpendicular to the width of the attachment, and each of the movable members 20' and 22' are provided with plates 40' and 42' slidable therewith, each of those plates being provided respectively with an elongated slot 92 and 94 respectively, each of those slots being inclined approximately 45 degrees with respect to the slot 50 and those slots at least partially overlapping, the pin 52 passing through the overlapping portions of the slots 92 and 94 and sliding along the slot 50. The coil spring 62a has one end 96a engaged against a tab 98 extending up from the base plate 2, the other end 100a of the spring 62a bearing against the pin 52 between the plates 40' and 42' and being active to urge the pin 52 toward the tubular part 4. It will be appreciated that the mode of operation of the embodiment of Figs. 7 and 8 will be substantially similar to that of the previously disclosed embodiment. The members 20' and 22' are connected together by means of the slots 92 and 94 in their respective plates 40' and 42' and by the pin 52 motion of which laterally of the attachment is effectively prevented, so that each of the members 20' and 22' will always be correspondingly positioned relative to the tubular part 4, thus providing for centering the attachment at all times. The inclination of the slots 92 and 94 will serve to resist inward movement of the members 20' and 22' when inward force is exerted only on one of those members. The spring 62a will be active to cause the members 20' and 22' to assume its outward telescoped positions, and only a portion of the inward force exerted on the members 20' and 22' will be applied to the spring 62a.

The embodiment of Fig. 9 is similar to that of Figs. 1-6 except that the spring 62b, instead of being wound around the pin 52, is instead confined within the housing portion 46b, one end 96b thereof being active against an end of the housing 46b and the other end 100b thereof being active against the hubs 58 and 60 of the arms 54 and 56 so as to urge those hubs, along with the pin 52, toward the tubular part 4. The embodiment of Fig. 10 is similar to that of Fig. 9 except that a specifically different location of the spring is disclosed, that spring being designated 62c, the end 96c thereof bearing against a side of the housing 46c and the end 100c thereof bearing directly against a tab 101 on one of the arm links.

In Fig. 11 a spring 62d is employed having ends 96d and 100d active on the movable members 20 and 22

independently of the linkage which connects them, those spring ends 96d and 100d engaging the inner ends of the plates 40d and 42d slidable respectively with the members 20 and 22. A spring 62d' may also be employed directly on the arms 54 and 56 so as to ensure that the trunnions 70 and 72 will remain within the slots 36 and 38 respectively, but the spring 62d' may be considerably weaker than the spring 62 in the embodiment of Figs. 1-6. Of course, a spring 62d' of normal strength could be employed, the springs 62d and 62d' thus assisting one another in urging the members 20 and 22 outwardly.

In the embodiment of Fig. 12 a tension spring 62e is employed, one end 96e of which is secured to a pin 102 extending up from the base plate 2, the other end 100e of which is secured to a pin 104 projecting from one of the hubs 58 or 60, the spring 62e, like the springs 62a, 62b and 62c, being active to urge the linkage to move so that the arms 54 and 56 pivot away from one another and the pin 52 moves along the slot 50 toward the tubular part 4.

From the above description it will be apparent that a simple and readily constructed and assembled end attachment has been devised which will reliably and positively provide a self-sizing feature, which will permit the use of weaker springs than have previously been employed without sacrifice of operating characteristics or, conversely, will provide improved operating characteristics with springs of conventional strength, and which will effectively retain the attachment centered between the lugs 16 of the watch 18 to which it may be attached against all normal dislocative forces which may be applied thereto.

While numerous detailed embodiments of the present invention have been here disclosed, it will be appreciated that they are merely illustrative of the many forms which this invention may take, all within the spirit thereof as defined in the following claims.

I claim:

1. A bracelet end attachment comprising a base having a part with sides adapted to be inserted between spaced watch lugs, a pair of longitudinally extending members on said base movable inwardly and outwardly with respect to the sides of said base part substantially in the direction of their length, resilient means active on said members to urge them outwardly, and a linkage operatively connected between said members and effective to require simultaneous movement of both members inwardly or outwardly with respect to said base part.

2. In the attachment of claim 1, a securing element mounted on said base so as to be movable between operative and inoperative position, said securing element when in operative position engaging said members when the latter are positioned inwardly with respect to the sides of said base part and retaining said members in that position.

3. A bracelet end attachment comprising a base having a part with sides adapted to be inserted between spaced watch lugs, a pair of longitudinally extending members on said base movable inwardly and outwardly with respect to the sides of said base part substantially in the direction of their length, resilient means active on said members to urge them outwardly, and a securing element mounted on said base so as to be movable between operative and inoperative position, said securing element when in operative position engaging said members when the latter are positioned inwardly with respect to the sides of said base part and retaining said members in that position.

4. The attachment of claim 1, in which said linkage is so constructed and arranged as to resist inward movement of said members upon the application of inwardly directed force to only one of said members.

5. The attachment of claim 1, said linkage comprising elements connected respectively to and movable with said

members, and a linking means operatively between said elements and movable substantially only in a direction perpendicular to the length of said members, said elements and said means being operatively connected so that said means moves toward and away from said body part as said members move outwardly and inwardly with respect to said body part, whereby inward movement of said members is resisted upon the application of inward force to only one of said members.

6. The attachment of claim 1, in which said linkage comprises a pair of arms pivotally connected respectively to said members and oriented at an angle with respect to the length of said members, and a movement-equalizing connection between said arms, whereby inward movement of said members is resisted upon the application of inward force to only one of said members.

7. The attachment of claim 1, in which said linkage comprises a pair of arms pivotally connected respectively to said members and oriented at an angle with respect to the length of said members, a pin pivotally connecting said arms to one another in overlapping relation, and means for preventing movement of said pin in the direction of movement of said members, whereby inward movement of said members is resisted upon the application of inward force to only one of said members.

8. A bracelet end attachment comprising a base, a fixed tubular part on said base adapted to be inserted between spaced watch lugs, a pair of longitudinally extending members telescopable into and out of opposite sides of said tubular part substantially in the direction of their length, resilient means active on said members to urge them outwardly, and a linkage operatively connected between said members and effective to require simultaneous movement of both members inwardly or outwardly with respect to said tubular part.

9. In the attachment of claim 8, a securing element mounted on said base so as to be movable between operative and inoperative positions, said securing element when in operative position engaging said members when the latter are positioned inwardly with respect to the sides of said tubular part and retaining said members in that position.

10. The attachment of claim 8, said linkage comprising elements connected respectively to and movable with said members, and a linking means operatively between said elements and movable substantially only in a direction perpendicular to the length of said members, said elements and said means being operatively connected so that said means moves toward and away from said body part as said members move outwardly and inwardly with respect to said body part, whereby inward movement of said members is resisted upon the application of inward force to only one of said members.

11. The attachment of claim 8, in which said linkage comprises a pair of arms pivotally connected respectively to said members and oriented at an angle with respect to the length of said members, a pin pivotally connecting said arms to one another in overlapping relation, and means for preventing movement of said pin in the direction of the length of said members, whereby inward movement of said members is resisted upon the application of inward force to only one of said members.

12. The attachment of claim 11, in which said members have slots opening outwardly from the inner ends thereof, and in which said arms have trunnions receivable in said slots, said trunnions and slots defining the pivotal operative connection between said arms and said members, whereby said operative connections may be effectuated by sliding said members inwardly through said tubular part until said slots receive said trunnions.

13. The attachment of claim 11, in which said members have slots opening outwardly from the inner end thereof, and in which said arms have trunnions receivable in said slots, said trunnions and slots defining the pivotal operative connection between said arms and said members, whereby said operative connection may be effectuated by

sliding said members inwardly through said tubular part until said slots receive said trunnions, said resilient means being active on said members via said linkage, whereby only a fraction of any inward force which may be exerted on said members is applied to said resilient means.

14. A bracelet end attachment comprising a base, a first tubular part on said base extending substantially in a straight line from side to side thereof and adapted to be inserted between spaced watch lugs, said tubular part having a slot therethrough extending longitudinally thereof between its interior and a surface of said base, a pair of longitudinally extending members telescopicable into and out of opposite sides of said tubular part substantially in the direction of their length, projections carried by said members and extending through said slot so as to overlie said base surface, resilient means active on said members to urge them outwardly, a linkage operatively connected between said members and effective to require simultaneous movement of both members inwardly or outwardly with respect to said tubular part, and a securing element mounted on said base surface so as to be movable between operative and inoperative positions, said securing element when in operative position engaging said projections when said members are positioned inwardly with respect to the sides of said tubular part and retaining said members in that position.

15. The attachment of claim 14, said linkage comprising elements connected respectively to and movable with said members, and a linking means operatively between said elements and movable substantially only in a direction perpendicular to the length of said members, said elements and said means being operatively connected so that said means moves toward and away from said body part as said members move outwardly and inwardly with respect to said body part, whereby inward movement of said members is resisted upon the application of inward force to only one of said members.

16. The attachment of claim 14, in which said linkage comprises a pair of arms pivotally connected respectively

to said members and oriented at an angle with respect to the length of said members, a pin pivotally connecting said arms to one another in overlapping relation, and means for preventing movement of said pin in the direction of the length of said members, whereby inward movement of said members is resisted upon the application of inward force to only one of said members.

17. The attachment of claim 16, in which said members have slots opening outwardly from the inner ends thereof, and in which said arms have trunnions receivable in said slots, said trunnions and slots defining the pivotal operative connection between said arms and said members, whereby said operative connections may be effectuated by sliding said members inwardly through said tubular part until said slots receive said trunnions.

18. The attachment of claim 16, in which said members have slots opening outwardly from the inner end thereof, and in which said arms have trunnions receivable in said slots, said trunnions and slots defining the pivotal operative connection between said arms and said members, whereby said operative connection may be effectuated by sliding said members inwardly through said tubular part until said slots receive said trunnions, said resilient means being active on said members via said linkage, whereby only a fraction of any inward force which may be exerted on said members is applied to said resilient means.
